UNITED STATES PATENT OFFICE.

CHARLES L. KEE, OF PORTSMOUTH, VIRGINIA.

ADVERTISING DEVICE.

Application filed November 19, 1924. Serial No. 750,819.

The present invention relates to an advertising device of the type embodying a sign having representations constituting a setting and a movable element organized and coacting with the setting in such manner as to actually depict successive stages in the use of a commodity, such as the dispensing and consumption thereof, or so as otherwise to draw attention to and create an interest in the subject of the advertisement.

One of the principal objects of the present invention is to provide an advertising device of this character wherein the setting with the movable element in one position is presented to view for a predetermined interval of time before the movable element is permitted to move to represent or depict the action which constitutes the central attractive feature of the advertising device.

By retarding the action of the movable element, that is, by preventing its movement for a predetermined period after the setting and movable element in one position have been presented to view, observers have an opportunity to grasp the import and significance of the first stage of the action represented before the movable element begins to progress through the various stages of the action. The action being easy to follow and attractive in subject-matter the attention of even the desultory is attracted and held so that the subject-matter of the advertisement is brought forcibly before the observers of the advertising device and interest in the subject of the advertisement is produced in the minds of the observers.

Another object is the provision of an advertising device of this character employing a sign having a plurality of faces adapted to be successively presented to view, the sign having on each of its faces a setting and having a movable element cooperable with each setting, the several faces of the sign serving to vividly depict several related actions in proper sequence.

Other objects and advantages reside in certain novel features of the construction, arrangement and combination of parts which will be hereinafter more fully described and particularly pointed out in the appended claims, reference being had to the accompanying drawings forming a part of this specification and in which:

Figure 1 is a view in front elevation showing a sign or advertising device constructed in accordance with the present invention,

Figure 2 is a fragmentary view in elevation showing the rear of the sign illustrated in Figure 1,

Figure 3 is a view in transverse section on line 3—3 of Figure 1,

Figure 4 is a view partly in elevation and partly in central vertical section illustrating the mechanism employed for controlling the movements of the movable element, and

Figure 5 is a similar view showing a different position of the parts.

Referring to the drawings, the numeral 1 designates a suitable base carrying pedestals 2 in which trunnions 3 of a sign frame 4 are rotatably mounted. The base 1 contains the motor for rotating the sign frame and this base and one of the hollow pedestals provide a housing for the motion transmission mechanism employed between the motor and sign. The motion transmission mechanism is of the type designed to intermittently move the sign frame through a predetermined angular interval. In the present instance an electric motor is used and the gearing employed rotates the sign frame through 180°, permits the same to remain stationary for a predetermined interval, then moves the sign frame through another 180° and again permits the same to remain stationary for a predetermined time and so on. The special details of this gearing forms no part of this invention.

A sign proper designated generally at 5 is fitted snugly within the main or rotating sign frame 4 and is held in position by elongated plates 6 which are attached by screws or other suitable fastening means to the sign frame 4 and which overlap the sign 5 to hold the same in position.

The sign proper consists of a rectangular frame 8 to which walls 9 and 10 are affixed. Between the spaced walls 9 and 10 a compartment 11 is formed. The exposed faces of the walls 9 and 10 bear representations which constitute the setting and major portion of the illustration of the sign. In the present instance this illustration consists of a voter about to drop a ballot into a ballot box. It is to be understood, however, that the subject-matter of the illustration may vary and that the illustration shown is merely for the purpose of disclosing one embodiment of the invention.

Each of the walls is provided with an opening 13 immediately above the ballot box depicted on the surface of the walls.

2

A solid frame 14 is positioned in the chamber or compartment 11 and is secured as at 15 to the frame 8. On the opposite sides of the frame 14 guides 16 are secured and receive 5 tongues 17 formed on a movable sign element 18 which is shiftable in the guides under the action of gravity. In the present instance the movable elements represent a ballot or the ballot of the group which the figures 10 represent or symbolize. The guides are so positioned that the sign element 18 is designed to move down across the opening 13 and thus appear to be dropped from the hand of the figure or voter into the ballot box. The portions of the frame 14 back of 15 the openings 13 are colored the same as the background of the exposed faces of the walls 9 and 10 so that the openings are camouflaged. Elastic bumpers 20 are provided 20 at the ends of the guides to limit the movements of the sign elements 18. Since the movable sign elements are freely shiftable in their movable guides under the action of gravity as each face of the sign is 25 presented to view, the ballot represented by its movable element will appear to drop into the ballot box and as each sign face is turned so as to be hidden from view its movable element will be repositioned so as to be 30 ready to drop into the ballot box the next time the sign face is presented to view. The present invention proposes to hold the movable sign elements 18 against shifting movement for a predetermined period after the 35 sign face with which they coat is presented to view so that the observers will have an opportunity to see the movable sign elements as constituting ballots in the hand of the voter and about to be dropped into the ballot box and after having opportunity to observe 40 this phase of the action, the movable sign element is released and the ballot apparently drops into the ballot box.

In carrying out these purposes, means is 45 provided for holding each movable element 18 in position to be elevated when its sign face is presented to view and this means is shown as comprising a latch 21 having a finger 22 adapted to be engaged with its 50 movable sign element 18. The end of the finger 22 which engages the sign element 18 is bevelled as at 23 to permit the sign 18 to reposition itself. The latch 22 is pivoted as at 24 on a bracket 25 and has an operating 55 arm 26 rigidly connected thereto and provided with a vertically offset end 27 which projects up into a casing 28 carried by the bracket 25 and by a second bracket 29, both of the brackets 25 and 29 being carried by 60 the frame 14. The vertically offset end 27 of the operating arm 26 of the latch 22 extends up into a guide socket 30 defined by two members 31 carried or fixed in the lower end of the casing 28. The casing 28 65 is of tubular form and has its ends closed.

One wall of the casing is removable. Within the casing 28 series of oppositely arranged guide members 32 are provided. The guide members 32 extend along each side of the casing and project toward each other and the 70 guide members on one side are arranged in between the guide members on the other side, or in other words the guide members are staggered. One side of each guide member is slightly inclined as indicated at 33 75 but the other side of each guide member is sharply inclined from its points as indicated at 34 and then gradually inclined toward its large end as indicated at 35. This arrangement of the guide members provides a tortuous passage for a steel ball 40 which under the action of gravity rolls from one end of the casing 28 to the other whenever the position of the sign is changed. The arrangement is such that when either 80 sign face is presented to view the ball organized with the mechanism associated with the front face rolls from the end at which the bracket 29 is located down the inclined face 33 of each guide until it finally falls into 85 the socket 30 and strikes the vertically offset end 27 of the operating arm 26 to swing the latch 22 about its pivot and disengage the finger 23 of the movable sign element 18 whereby to permit the sign element to 90 shift across its opening 13. By virtue of the slight inclination of the sides 33 of the guides the movement of the ball to position to release the latch 22 is relatively slow and requires an interval of time sufficient to permit observers of the sign to fully grasp the import and significance of that phase of the 95 action illustrated when the movable sign element 18 is held elevated. As the face which has been presented to the front moves to the back the ball organized with the mechanism associated with such face rolls from the end at which the bracket 25 and socket 30 are located down to the end at 100 which the bracket 29 is located and the ball moves rapidly at such time since it travels over the sharply inclined portions 34 of the guides. This quick return of the balls insures a full and complete retarding action. Light retractile coil springs 45 are associated 105 with the latches 22 and tend to project the fingers 23 into engagement with the movable sign elements.

I claim:

1. In an advertising device, a sign having a wall adapted to be periodically presented to view, said wall having an opening, an element biased to shift across the opening when the wall is presented to view, and means for preventing shifting movement of the element for a predetermined interval after the wall has been presented to view. 120
2. In an advertising device, a sign having a wall adapted to be periodically presented to view, said wall having an opening, an 125
- 130

element shiftable across said opening under the action of gravity when the wall is presented to view, means coacting with the element for holding the same against movement, and a release for said means operable at a predetermined interval after the wall has been presented to view.

3. In an advertising device, a sign having a plurality of walls adapted to be successively presented to view, each wall having an opening, a movable sign element shiftable across said opening, means coacting with said element for holding the same against movement and a release for each means operable at a predetermined interval after the wall with which it is associated is presented to view.

4. In an advertising device, a sign having a plurality of walls adapted to be successively presented to view, each wall having an opening, guides associated with each opening, a movable sign element for each opening, each sign element being mounted for free shifting movement in the guides associated with its opening, a latch cooperable with each sign element, a release for each latch including a casing and a ball shiftable in the casing under the action of gravity,

each casing having a plurality of guides therein defining a tortuous passage to retard the movement of the ball. 30

5. An advertising device of the character specified in claim 4 and wherein the guides of the casing which define the tortuous passage for the ball have slightly inclined sides 35 to constrain the ball to slow movement when the same is moving to release the latch and sharply inclined portions to permit a quick return of the ball.

6. In an advertising device, a sign, means 40 for mounting the sign for turning movement about a horizontal axis, said sign including a frame and spaced walls secured to the frame and defining a compartment, each wall having representations thereon and 45 having an opening, a frame arranged within the compartment and connected with the frame of the sign, guides on said frame for the openings of each wall, a movable sign element in each set of guides, each movable 50 sign element being shiftable under the action of gravity across the opening of the wall with which it is associated, a latch for holding each movable sign element against movement and means for releasing the latch.

CHARLES L. KEE.
